The ornamental design for a patio umbrella, as shown and described.

DESCRIPTION

FIG. 1 is a bottom perspective view of a patio umbrella showing my present design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top perspective view thereof;

FIG. 9 is a schematic view of FIG. 1 in a use state; and,

FIG. 10 is a schematic view of FIG. 1 in another use state. The representations of the design are in greyscale; the design does not claim protection for a specific coloring. The broken lines shown in FIG. 9 and FIG. 10 are for illustrative purposes only and form no part of the claimed design.
